UNITED STATES PATENT OFFICE.

GEORGE W. BORTON, OF NEW LISBON, NEW JERSEY, ASSIGNOR TO PENNSYLVANIA CRUSHER COMPANY, OF NEW YORK, N. Y., A CORPORATION OF NEW YORK.

HAMMER MILL.

Application filed February 14, 1928. Serial No. 254,235.

This invention relates to hammer mills, and relates more particularly to a novel and highly advantageous construction in those parts providing the breaking surface.

5 The principal object of the invention is to provide a breaking surface which is self-cleaning and which prevents the accumulation of dust and other materials on the breaking surfaces, or plugging up, with the consequent material loss in efficiency.

10 Another object of the invention is to provide a breaking surface structure having self-cleaning characteristics actuated by the impact of the materials impelled against the breaking surface by the hammers.

15 In the attached drawings, in which I have illustrated a hammer mill of the "bottom running" type:

20 Figure 1 is a more or less diagrammatic sectional view showing sufficient of the details of a hammer mill to afford an understanding of the invention, and

25 Fig. 2 is a section on the line 2—2, Fig. 1.

With reference to the drawings, 1 represents the casing or housing of the mill and 2 the rotary shaft which carries a rotor 3 having the pivoted hammers 4. As previously stated, the hammer crusher is of the type known as "bottom running", and the rotor 3 with the hammers is accordingly rotated in the direction of the arrow, see Fig. 1. The material is fed into the casing at the top and is impelled by the rotating hammers against the upper breaking plate or surface 5, and thereafter against and over the surface of the cage 6, which in the present instance is pivotally mounted at one end on a transverse shaft 7.

30 The upper or advance end of the cage 6, as clearly illustrated in Fig. 1, comprises a plurality of independent bars 8 pivotally mounted upon a transverse shaft 9 in the cage structure, and the bars 8 form a breaking and crushing surface against which the material 35 is impelled by the hammers in well known manner. In back of or underneath the upper and lower ends of the series of bars 8 are stop shafts or transverse rods 10, 10, which limit the oscillatory movement of the bars 40 around the shaft 9 upon which they are journaled. Preferably the shaft 9 is normal to the general direction in which material entering the crusher is impelled by the hammers, and the rods 10, 10, prevent a material

45 departure of the bars 8 from a plane normal to the direction of movement of the said material.

50 Although not essential to the invention, I prefer to provide at the back of each of the bars 8, secured thereto respectively on each side of the shaft 9, a pair of springs 11 and 12 which also are adjustably secured to the housing 1 by means of the threaded eye bolts 13 projecting through suitable bosses 14 on the housing and held in said bosses by means 55 of retaining nuts 15 threaded on the said studs or bolts on the outside of the housing. These springs, as will be apparent, tend to retain the bars 8 in a normal position clear of both the stop rods 10, so that upon impact either 60 above or below the shaft 9, the bars 8 are free to oscillate or vibrate to an extent limited by the stops 10 or the pressure or tension of the springs 11 and 12. The tension of the springs 11 may be adjusted through the studs 13 and 65 adjusting nuts 15 to provide a proper flexible balance in the bars 8.

70 When material is fed into the housing 1 and is impelled by the hammers 4 against the surface formed by the bars 8, a vibratory or oscillatory movement will be set up therein around the pivot bar 9, this movement being controlled by the springs 11 and 12, the bars being returned after each successive shock to a normal position by the springs. By reason 75 of the vibratory or oscillatory movement set up in the bars, and the shock due to impact of the bars against the stop bars 10, material such as wet dust or other adherent substances, 80 having a tendency to fill the spaces between 85 the bars and eventually to cover the bars in such manner as to reduce their operating efficiency, will be shaken or jolted from the bars.

90 It will be noted that the vibratory or oscillatory movement of the bars is set up by the material impelled against them in normally passing through the mill. Attention is also directed to the extremely desirable action obtained by the described arrangement of parts, 95 combining a vibratory movement of the bars around the shaft 9 with a severe shock due to the impact of the ends of the bars against the respective stop bars 10, 10 tending to dislodge any substances adhering to the bars, 100 and thereby keeping them clean.

105 Although I have illustrated and described the bars as having associated springs 11 and

12, it will be apparent that these springs may under some circumstances be entirely eliminated without departure from the essential features of the invention, the irregular 5 impact of the material on opposite sides of the transverse journal bar 9 being sufficient to set up the desired vibration or oscillation of the bars, with consequent shock arising from impact against the stop bars.

10 The type of material passing through the mill and the particular conditions of operation will determine whether or not to dispense with the springs and to otherwise modify the structure. It may for example 15 be desirable to place the transverse bar 9 to one side of the middle of the bars 8, and the center of oscillation may be thus so located as to provide a maximum oscillation of the bars due to impact there against the 20 material passing through the crusher.

Although I have illustrated the invention as applied to a "bottom running" hammer mill, it will be apparent that it may be usefully applied to any type of mill regardless 25 of the relation between the hammer rotor and the crushing surfaces, and the invention is in no sense limited to the particular application herein illustrated and described.

I claim:

30 1. A hammer mill comprising a housing, a rotor in said housing including a plurality of hammers, means for feeding material into the housing so as to be brought into engagement with the hammers, and a structure providing a crushing surface against which the said material is impelled by the hammers, said structure including a transverse shaft and a plurality of bars pivotally mounted on said shaft intermediate their ends and oscillatable under impact of said material, and 35 means for limiting the oscillatory movement of the bars in both directions.

2. A hammer mill comprising a housing, a plurality of rotary hammers mounted for 40 rotation in the housing, and a self-cleaning crushing surface against which the hammers are adapted to impel a material introduced into the mill, said crushing surface structure including a plurality of surface forming bars 45 pivotally mounted in spaced and substan-

tially parallel relation adjacent the rotor and oscillatable under impact of said material.

3. A hammer mill comprising a housing, a plurality of rotary hammers mounted for rotation in the housing, and a self-cleaning 50 crushing surface against which the hammers are adapted to impel a material introduced into the mill, said crushing surface structure including a plurality of surface forming bars mounted for oscillation in spaced and substantially parallel relation adjacent the rotor, and resilient means controlling the oscillation of said bars.

4. A hammer mill comprising a housing, a plurality of rotary hammers mounted for 55 rotation in the housing, and a self-cleaning crushing surface against which the hammers are adapted to impel a material introduced into the mill, said crushing surface structure including a plurality of surface forming bars 60 mounted for oscillation in spaced and substantially parallel relation adjacent the rotor, and resilient means controlling the oscillation of said bars, with positive stops 65 limiting the oscillation of said bars.

5. A hammer mill comprising a housing, a rotor in said housing including a plurality of hammers, means for feeding material into the housing so as to be brought into engagement with the hammers, and a structure providing a crushing surface against which the said material is impelled by the hammers, said structure including a transverse shaft and a plurality of surface-forming bars 70 mounted for oscillation under impact of said material about an axis intermediate the ends thereof, and stops limiting oscillation in both directions.

6. An impact crushing surface composed of a plurality of bars each pivotally mounted 75 intermediate its ends on an axis substantially normal to the direction of movement of the impacting material and oscillatable under said impact, and means for limiting the oscillation of the bars in both directions so 80 that the bars cannot materially depart from a plane normal to the movement of said impacting material.

GEORGE W. BORTON.
